US00D774526S

(12) United States Design Patent (10) Patent No.: US D774,526 S
Klein et al. (45) Date of Patent: * Dec. 20, 2016

(54) DISPLAY SCREEN WITH GRAPHICAL USER INTERFACE FOR FUNDS TRANSFER

(71) Applicant: Bank of America Corporation, Charlotte, NC (US)

(72) Inventors: Charmaine Klein, Charlotte, NC (US); Christopher G. Gagliardo, Charlotte, NC (US); Abla L. Hamilton, Santa Cruz, CA (US); Peter Nies, San Francisco, CA (US)

(73) Assignee: BANK OF AMERICA CORPORATION, Charlotte, NC (US)

() Term: 14 Years

(21) Appl. No.: 29/491,068

(22) Filed: May 16, 2014

Related U.S. Application Data

(63) Continuation-in-part of application No. 29/385,831, filed on Feb. 21, 2011, now Pat. No. Des. 708,628.

CLAIM

The ornamental design for a display screen with graphical user interface for funds transfer, as shown and described.

DESCRIPTION

The FIGURE depicts a view of a design for a display screen with graphical user interface for funds transfer.

The outermost broken line drawing of the display screen and all other broken line drawings of the images, text, and other elements are included for the purpose of illustrating portions of the article and form no part of the claimed design.

Inside the Bank

Set Up Email Address or Mobile Number to Accept Transfers
 if you received a notice that someone sent you money, you will need to set up the same email address or mobile number that received the transfer notice.

Enter your email address or mobile number: 415-555-1212
 (Example: name@email.com, XXX-XXX-XXXX)

Confirm your email address or mobile number: 415-555-1212
 (Example: name@email.com, XXX-XXX-XXXX)

Select an account to receive the funds: Savings 1234

By registering this email address or mobile number, I agree that I am the email or mobile number account holder, or have the account holder's permission to register it, and I consent to receive email and automated text messages about Email/Mobile Transfers at the email address or mobile number. Please Note: This information will be saved for any transfers sent to you at the email address or mobile number you provided.

To complete setup, select Continue and get your enrollment code.

Set Up Email Address or Mobile Number to Accept Transfers
if you received a notice that someone sent you money, you will need to set up the some email address or mobile number that received the transfer notice.

Enter your email address or mobile number: 415-555-1212
(Example: name@email.com, XXX-XXX-XXXX)

Confirm your email address or mobile number: 415-555-1212
(Example: name@email.com, XXX-XXX-XXXX)

Select an account to receive the funds: >

By registering this email address or mobile number, I agree that I am the email or mobile number account holder, or have the account holder's permission to register it, and I consent to receive email and automated text messages about Email/Mobile Transfers at the email address or mobile number.

Please Note: This information will be saved for any transfers sent to you at the email address or mobile number you provided.

To complete setup, select Continue and get your enrollment code.
